(57) **CLAIM**

The ornamental design for a mobile phone stand, as shown
and described.

DESCRIPTION

FIG. 1 is a perspective view of a mobile phone stand
showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the mobile phone stand where
the mobile phone stand is in a configuration of use.

The broken lines shown in the figures that are immediately
adjacent to the shaded areas and define unshaded regions
represent the bounds of the claim. All other broken lines,

(Continued)

including the features within broken line boundaries, are directed to environment. The broken lines form no part of the claimed design.

1 Claim, 9 Drawing Sheets
